COMBINATION LATHE-TOOL

Andreas C. Nielsen, East Cleveland, Ohio

Application October 13, 1943, Serial No. 506,120

1 Claim. (Cl. 29—48)

My invention relates broadly to a combination lathe-tool, comprising one or several individually mounted cutters or bits well understood by others skilled in the art.

The object of this invention is to provide a simple construction having efficient means for the purpose of facilitating the tool setting preparatory to turning.

The stop engaging member mounted in the base has a slight rotational movement to compensate for the exact want of alignment of the stop receiving groove formed in the removably and adjustably mounted stop member or members in the tool carrying member, thus obviating the effort of positioning the tool mounting to an exact index marking as is usual with a tool mounted on a compound rest on a lathe.

The invention consists substantially in the construction, combination and arrangement of parts hereinafter set forth as shown by the accompanying drawings and finally pointed out in the appended claim.

Reference is to be had to the accompanying drawings forming a part of this specification in which like reference characters indicate corresponding parts throughout the several views.

Figure 1 is a top plan view of the combination lathe-tool, one of the closure plates 66 has been removed to show the arcuate slot in the plate 37, and its approximate position therein between the cheek carrying posts.

Figure 2 is a plan view of the base and further illustrating the approximate position of the stop engaging member 15, and the handle 16 by means of which it is manipulated.

Figure 3 is an end view of the T shaped member.

Figure 4 is a side view of the T shaped member shown in Figure 3.

Figure 5 is a sectional view taken on line A—A in Fig. 1.

Figure 5A is a bottom view of Figure 5 taken on the line C—C, the base has been removed to disclose the recess in the tool carrying member, and also the removably mounted adjustable segmental sections in the recess.

Figure 6 is a plan view of one of the segments separated from the tool carrying member.

Figure 7 is an edge elevation of the segment shown in Fig. 6.

Figure 8 is a plan view of one of the closure plates separated from the tool carrying member.

Figure 9 is an edge elevation of the closure plate shown in Figure 8.

Figure 10 is a top plan view of one of the cheek plates, removed from the cheek carrying post.

Figure 11 is a view in side elevation of the cheek plate shown in Figure 10 looking in the direction of the arrows B—B in Figure 10 to illustrate the position of the chamber 50 therein.

Figure 12 is a top plan view of the shouldered nut 39 with its socket fillister head cap screw 52.

Figure 13 is a side view of the shouldered nut shown in Fig. 12.

Figure 14 is a plan view of the stop engaging member 15 mounted in the base 10, clearly shown in position in Figure 2.

Figure 15 is a side view of the stop engaging member shown in Figure 14.

Figure 16 is a front view of the stop engaging member shown in Figures 14 and 15.

Figure 17 is a side view of the stop engaging member and the handle by means of which it is manually operated in the base.

Figure 18 is an end view of the handle shown in Figure 17 illustrating the position of the eccentric pin thereon.

Figure 19 is a top plan view of a variant of a tool carrying member that may be mounted on the base shown in Figure 2, the tool carrying member being provided with a boring bar, the boring bar being shown fragmentary.

Figure 20 is a side view of the variant shown in Figure 19.

Figure 21 is a plan view of the grooved ring that may be adjustably mounted in the recess provided in the tool carrying member shown in Figures 19 and 20.

The base 10 is formed with an eccentric 11, and a perpendicular cylindrical tubular member 12 having a common center with the eccentric. The upper end 13 of the aforesaid cylindrical member is provided with an external screwthread 14 for the reception of the nut 33. In the base there is provided a vertically positioned movable stop engaging member 15 which is manipulated by means of the handle 16.

The stop engaging member comprises a solid cylindrical portion 17 having its periphery interrupted to provide a flat surface as at 18. In the cylindrical portion there is provided a transverse groove 19 for the reception of the eccentrically positioned pin 23 integrally formed on the end of the cylindrical portion 22 of the handle 16. The portion 21 of the stop engaging member is reduced and is adapted to engage in a groove formed in the segment or ring herein-
66 after described.

In the solid cylindrical portion 22 of the handle 16 there is provided a through bore 24 adapted to receive the pin 25, the portion 26 of which projects beyond the cylindrical portion and is adapted to engage the upper wall of the elongated recess 27 formed in the underside of the base. Detail views of the stop engaging member and the handle are shown in Figs. 14, 15, 16 and 17. The recess 27 in the base is shown in Figs. 1 and 2 in dotted lines, and the relation of the portion 26 of the pin in the recess is also shown in Figs. 1 and 2. A detail view of the pin extending out from the cylindrical portion 22 of the handle 16 is shown in Figs. 17 and 18.

The projecting portion 26 of the pin is adapted to limit the rotational movement of the handle to 180° in its movement in the base by engaging the upper wall of the recess 27 formed therein. When the handle is turned clock-wise, the stop engaging member is released from the groove formed in the segment or ring mounted in the recess formed in the tool carrying member, and when turned counter-clockwise it is moved upward into the groove. The movement is imparted to the stop engaging member by means of the eccentric pin 23 on the end of the cylindrical portion of the handle acting as a cam in the transverse groove 19 formed in the stop engaging member. The aforesaid movement transmitting means is longitudinally mounted in the base 10, see Fig. 1. The stop engaging member has a slight rotational slack in the base to compensate for want of exact alignment of the groove formed in the segment or ring. In the arrangement of the parts shown in the detail assembled view shown in Fig. 17, it will be noted that the end of the cylindrical portion 22 is spaced apart a short distance from the flat face 18 on the stop engaging member, this construction allows the stop engaging member to rotate slightly to enter the groove in the segment or ring should it be out of exact alignment with the portion 21.

The T shaped member 28 is adapted to fit in the slot provided to receive the same in the conventional compound rest on a standard lathe, and the base 10 is held in clamped position thereon by means of a socket fillister head cap screw 29 that extends down through the perpendicular cylindrical portion on the base to thread into the threaded bore 30 provided therein to receive the same. The aforementioned T shaped member 28 and the socket fillister head cap screw 29 is provided to clamp the base on the compound rest of the lathe, well understood by those skilled in the art.

On the base there is removably mounted a rotatable tool carrying member 31 and is held thereon by means of friction washer 32 and the nut 33. The tool carrying member is provided with a plurality of spaced perpendicular cheek plate carrying posts as at 34, 35 and 36, shown in the plan view Fig. 1. As these cheek plate carrying posts are all of similar construction, it is thought that a description of one of them will suffice for all. The cheek plate carrying post is integrally formed with the plate portion 31 of the tool carrying member and is provided with a vertically extending elongated through slot 38 for the reception of the slidably mounted nut 39, which is provided with a threaded bore 40 and a shoulder 41 at one end, provided to prevent the nut slipping through the slot formed in the cheek plate carrying post in which it is mounted. Detail views of the nut 39 with a socket fillister head cap screw

52 threaded therein are shown in Figs. 12 and 13. In the plate portion 37 of the tool carrying member 31 adjacent its bottom surface there is provided fixedly mounted horizontally extending studs 42, 43 and 44, all alike, one being provided for each cheek plate, these studs are shown clearly in the bottom view of the tool carrying member 31 in Fig. 5A.

10 In the face of each of the cheek plate carrying posts there is provided a vertically extending parallel groove 45, see position of the grooves in Fig. 1. The surface remote from the groove is angularly inclined as illustrated in Fig. 1 at 46.

15 The cheek plate 47 in which the tool bit 48 is removably and adjustably secured by means of the set screw 54 is machined to fit the cheek plate carrying post with accuracy, and the integrally formed rib 49 on the cheek plate slidingly fits in the groove 45 formed in the cheek plate carrying post and is adapted to keep the cheek plate in exact alignment thereon as well as to assist in taking the thrust on the tool bit in the machining operation. In the cheek plate there is provided a chamber 50 remote from the rib 49 but parallel therewith that extends from its bottom surface part way up its length and into which one of the fixedly mounted horizontally extending studs may extend. The chamber 50 in the cheek plate is shown in the bottom view of the tool carrying member in Fig. 5A, and also in the detail views of the cheek plate shown in Figs. 10 and 11. A set screw 51 in the cheek plate extends vertically downward into the chamber 50, and is adapted to engage the horizontally extending stud projecting from the plate portion of the tool carrying member thereinto. See position of the aforementioned studs in Fig. 5A.

20 30 35 40 45 50 55 60 65 70 75 80 85 90 When the socket fillister head cap screw 52 in the counterbore 53 in the cheek plate 47 is released in the nut 39 mounted in the cheek plate carrying post, the set screw 51 in the cheek plate with its tool bit 48 may be screwed down against the stud extending into the chamber 50 to force the cheek plate upward on the cheek plate carrying post to adjust the height of the tool bit carried thereby, and when the set screw 51 is screwed upward the cheek plate may be manually forced downward to properly position the tool bit relative to the stock being machined. The socket fillister head cap screw 52 is adapted to clamp the cheek plate against the cheek plate carrying post through its cooperation with the shouldered nut.

The tool bit is held in position in the cheek plate by means of the set screw 54 that is threaded into the cheek plate and engages the tool bit as shown in the detail view in Fig. 11.

In the bottom surface of the plate portion 37 there is provided an annular recess 55 concentric with the eccentric 11 on the base 10, in which an annular ring 56 as shown in Fig. 21 or a plurality of segmental sections such as that shown in the bottom view in Fig. 5A at 57, 58 and 59 may be adjustably and removably mounted therein.

60 65 70 75 80 85 90 The ring or segment may be provided with one or more stop engaging grooves as shown at 60 and 61, see Fig. 21, or as at 62 in the segment. See detail views 6 and 7, also the segments in place in the bottom view Fig. 5A.

In the plate portion 37 there is provided a plurality of curved or arcuate elongated slots positioned between the cheek plate carrying posts disposed in a circle as at 63, 64 and 65. See the position of the aforesaid slots in the dotted lines in Fig. 5A, also in Fig. 1 under the closure plates 66. In Fig. 1, one of the closure plates 66 has been

removed to clearly show the position of the arcuate slot in the plate portion 37, and the segment below in the recess.

A closure plate 66 is provided for each of the aforesaid arcuate slots, and each is provided with a hole 67 through it for the reception of a socket fillister head cap screw 68 that extends through the closure plate, the plate portion 37 of the tool carrying member 31 to engage in a threaded bore in the segment or ring adapted to receive the same. The socket fillister head cap screw is provided to hold the closure plate in place over the arcuate slot, and also to secure the segment or ring in place in the recess 55, before and after adjustment. The curved or arcuate slots are provided to permit the adjustment of the tool carrying member 31 on the base rotationally. The closure plate 66 is adapted to keep the metal chips out of the slots, and also to act as a friction washer under the socket fillister head cap screw.

When it is necessary to adjust the tool bit rotationally relative to the stock being machined, the predetermined socket fillister head cap screw is released, thus releasing the segment or ring in the recess 55, after which the tool carrying member may be rotated slightly to the right or the left to bring the tool bit in to proper position, and when properly positioned the released socket fillister head cap screw is tightened, securing the tool carrying member in position on the base.

It is obvious that the down-time for tool grinding and resetting is cut down to a minimum, and production may be stepped up. Furthermore the tool bit is solidly clamped and supported with a minimum of overhang.

In the variant shown in Figs. 19 and 20, a boring bar holder 69 is mounted on the base shown in Fig. 2 to illustrate how various tool carrying members may be substituted thereon. To remove the tool carrying member and replace it with another, the nut 33 and the washer 32 are removed and the selected tool carrying member placed on the base, the washer and nut restored to their respective place, then the ring or segments are adjusted to meet the exigencies of use.

A face plate for a lathe is shown at 70 with a standard lathe dog 71 mounted on a piece of stock centered on a lathe center mounted in the headstock spindle in the well known manner and familiar to those skilled in the art. The combination lathe-tool, with one of its tool bits in operative position is shown in Figure 1.

It is believed that the operation of the combination lathe-tool will be clear, in view of the foregoing description which has been given in connection with that of the construction.

I am aware that my invention may be embodied in other specific forms without departing from the spirit or essential attributes thereof; and I therefore desire that the present embodiments to be considered in all respects as illustrative and not restrictive, reference being had to the appended claim rather than to the foregoing description to indicate the scope of the invention.

Having thus described my invention, what I claim is:

In a device of the class described, comprising, in combination, a base having an elongated re-

cess formed in the bottom surface thereof, an eccentric portion on its upper surface, a perpendicular cylindrical tubular portion concentric with the eccentric, the upper end of which is provided with an external screwthread, a handle having a cylindrical portion having a through bore therein and an eccentrically positioned pin on the end thereof, longitudinally mounted in the base, a pin mounted in the through bore in the cylindrical portion of the handle and having a portion thereof projecting therefrom to engage the upper wall of the elongated recess formed in the base to limit the rotation of the handle in the base, a stop engaging member mounted in the base vertically to the longitudinally mounted handle, having a reduced upper portion, and having a flat surface formed thereon having a transverse groove formed therein to receive the eccentrically positioned pin on the handle, the handle being adapted to actuate the stop engaging member through the eccentrically positioned pin thereon acting as a cam in the transverse groove, a tool carrying member comprising a plate having an annular recess formed in the under surface thereof concentric with the eccentric on the base, a plurality of perpendicular arranged cheek plate carrying posts integral with the plate portion, the plate portion having arcuate slots formed therein between the cheek plate carrying posts, the cheek plate carrying posts each being provided with a vertical elongated through slot, and having adjacent thereto a parallel vertical groove, fixedly mounted longitudinally extending studs mounted in the plate portion adjacent its lower surface, a cheek plate removably and adjustably mounted on each cheek plate carrying post and provided with an integral rib and also having a chamber formed therein parallel to the rib but remote therefrom, the rib engaging in the parallel groove in the cheek carrying post, and the chamber receiving one of the fixedly mounted longitudinally extending studs, a set screw in the cheek plate and extending into the chamber to engage the stud extending thereinto, a socket fillister head cap screw in the cheek plate adapted to hold the cheek plate on the cheek plate carrying post through its co-operation with a shouldered nut slidably mounted in the vertical elongated through slot in the cheek plate carrying post, a tool bit removably and adjustably mounted in the cheek plate and held therein by a set screw, a plurality of grooved segments removably and adjustably mounted in the recess in the plate portion, a closure plate having a hole therethrough to cover an arcuate slot in the plate portion, a socket fillister head cap screw passing through the hole in the closure plate and down through the arcuate slot formed in the plate portion to engage in a threaded bore in the segment mounted in the recess in the plate portion to secure the segment, a friction washer mounted on the cylindrical tubular portion and a nut threaded thereon to secure the tool carrying member on the base, and a socket fillister head cap screw passing down through the cylindrical tubular portion and threadedly engaging a T shaped member cooperating therewith to secure the device on a lathe.

ANDREAS C. NIELSEN.
